CLAIM

The ornamental design for a combination easy release wristband and label form, as shown and described.

DESCRIPTION

FIG. 1 is a front view of the combination easy release wristband and label form; and,

FIG. 2 is a back view of the combination easy release wristband and label form of FIG. 1.

The dash-dot-dash lines in FIG. 1 illustrate die cuts and form part of the claimed design. The dashed lines shown in the Figures do not form a part of the claimed design.

1 Claim, 2 Drawing Sheets
